COMBINATION FOOTREST AND CHAIR

Glenn R. Smith, Los Angeles, Calif., assignor of
one-half to Nellie R. Smith, Santa Barbara,
Calif.

Application October 11, 1941, Serial No. 414,617

5 Claims. (Cl. 155—169)

This invention relates to the furniture art, and has as its objects to provide an improved tilting footrest and to provide a combination tilting footrest and low chair or stool.

A further object of the invention is to provide a tilting footrest which is, in its inclined position, suitable for use as a child's chair.

Another object of the invention is to provide a tiltable footrest which when in inclined position may be readily and comfortably operated by the user even though the floor engaging portions of the base of the footrest are substantially spaced in front of the chair occupied by the user.

It is another object of the invention to accomplish the aforesaid objects by a simply constructed article of furniture which affords comfort to the user in each of its several positions, and which is attractive in appearance.

In the drawing, which is for illustrative purposes only:

Fig. 1 is a plan view of a footrest embodying the invention in one form.

Fig. 2 is a vertical sectional view of the footrest shown in Fig. 1, taken along the line 2—2 of Fig. 1, the platform deck of the footrest being shown in full lines to represent the position which it occupies when the footrest is to be used as a low chair or stool, and in phantom lines to represent the two extreme positions which it occupies when used as a tiltable footrest.

Fig. 3 is an end view of the footrest shown in Figs. 1 and 2, taken in the direction of the arrow on Fig. 2.

Fig. 4 is a fragmentary vertical sectional view taken along the line 4—4 of Fig. 1, the platform deck being shown in phantom lines.

Fig. 5 is a plan view of another embodiment of the invention.

Fig. 6 is a vertical sectional view taken along the line 6—6 of Fig. 5, showing the platform in its several positions by means of full lines and phantom lines respectively, as in the showing in Fig. 2.

Referring to Figs. 1 to 4, inclusive, the combination footrest and chair comprises a base 11 and a platform deck 12. The base 11 has two side elements 13 and 14 and three cross rails 15, 16, and 17 which unite the side elements to form a rigid base assembly. The side elements 13 and 14 are each shaped to have an upper horizontal portion 18 extending longitudinally of the base, a front leg 19, and a rear leg 20, these legs serving to support the combination chair and footrest upon the floor 21.

It will be understood that the base 11 may be

designed and constructed in many different ways without departing from the principles of the invention. Thus, the side elements 13 and 14 may be generally rectangular plates of wood or metal; instead of the cross rails 15 and 16 there may be used wide boards extending to the floor, giving the base a box-like construction; and the base may be constructed wholly or in part of tubular steel. Also the side elements may be upholstered as desired to improve the appearance of the article of furniture and to suit any particular purpose for which it is designed.

The upper portion 18 of each of the side elements 13 and 14 is formed with a guideway 22. 15 In the particular embodiment of the invention shown in Figs. 1 to 4, the side elements 13 and 14 are of wood and the guideways 22 are shallow elongated recesses or grooves on the inner side faces of the side elements 13 and 14. Such grooves 20 are termed "routs" in the woodworking art.

Each rout 22 extends longitudinally of the upper portion 18 of the side elements from a forward point 23 (see Fig. 4) slightly in front of the median line of the side elements, rearwardly and 25 upwardly at a slight angle to the horizontal to a rear end wall 24. Each rout 22 has an upper wall 25 and a lower parallel wall 26. The lower wall 26 is provided with a shallow notch or depression 27 at a point along the rout 22 slightly nearer the forward end 23 than the rear end wall 24. The upper rout wall 25 and the end wall 24 30 intersect the upper face 28 of the side portion 18 to provide an opening 29 at the rear end of the rout.

The platform deck 12 has a platform portion or seat 30 and a transverse member or back 31, the transverse member 31 extending outwardly from the front end of the seat 30 preferably at an angle to the seat of slightly more than 90°. While for convenience of reference the platform portion 30 is herein termed a seat and the transverse member 31 is termed a back, the platform portion 30 serves as a seat, as a foot-and-leg rest, or as a chair back according to the position of the platform deck with reference to the base and in accordance with the use to which the article of furniture is put, and similarly the transverse member 31 may serve as a chair back, foot support, or chair seat. These several alternative uses of the two parts of the platform deck will appear in the course of the description of the operation of the article of furniture.

The seat 30 and back 31 are rigidly secured between platform deck side members 32, each having a horizontal arm 33 to which the seat 30 is

secured and an upright arm 34 to which the back 31 is secured. The seat 30 and back 31 may be suitably upholstered as shown at 35 and 36, respectively.

The seat 30 of the platform deck is provided with two oppositely directed horizontal hinge pins 37, each projecting transversely outwardly from the corresponding side of the seat 30. One desirable method of constructing the pins and securing them to the seat 30 is shown in the drawings. A reinforcing cross bar 38 is secured to the under horizontal edges of the side members 32 and is formed at each end with a pin 37, each pin projecting a short distance beyond the outside face of the corresponding side member 32. Each pin 37 projects into the corresponding rout 22 and is of a diameter slightly less than the width of the rout 22, enabling it to slide longitudinally of the rout and to be restrained from vertical movement by the upper and lower walls of the rout. It will be understood that while one form of guideway for the pin 37 has been illustrated and described in the rout 22 and one form of an element on the platform deck for engaging the rout has been described in the pin 37, other forms of guideways on the base and engaging elements on the platform deck may be substituted therefor without departing from the spirit of this invention. Portions or all of the upper wall 25 of the guideway may be dispensed with without loss of some of the advantages of the invention. Also, the relative positions of the guideway and pin may be reversed, the guideway being provided on the platform deck and the engaging member or pin on the base.

The platform deck is provided with a pair of oppositely directed stop pins 39 formed upon the ends of a reinforcing cross bar 40 which is secured between the inner side faces of the side member 32 and preferably lies against the under surface of the seat 30. The stop pins 39 extend through apertures 41 in the side members 32 and beyond the outer side faces of the side members 32 to project into the routs 22 and engage these routs in a manner similar to that of the engagement of the pins 37 with the routs 22.

The reinforcing bar 40 and pins 39 are so disposed longitudinally of the seat 30 that the distance between the stop pins 39 and hinge pins 37 is somewhat greater than the length of that portion of the routs between their front ends 23 and the notches 27. This distance is also such that when the hinge pins 37 are seated in the notches 27, the stop pins 39 are adjacent the end walls 24 of the rout 22 and directly beneath the rout openings 29.

In describing the operation of the article of furniture, the position of the platform deck upon the base, identified by the letter "A" and shown in full lines in Fig. 2, will first be described. In this position the hinge pins 37 are seated in the front ends 23 of the routs 22 and the stop pins 39 are seated in the routs 22 just behind the notches 27. The difference in spacing of the hinge pins 37 and stop pins 39 from the under side of the seat 30 and the inclination to the horizontal of the routs 22 are such that in this position the seat is substantially horizontal. Engagement of the hinge pins and the stop pins with the upper and lower walls of the rout prevents tilting of the platform deck in either direction on the base. In this position of the platform deck with respect to the base, the article of furniture serves as a low chair or stool.

If, now, the platform deck be moved to the rear

either by pushing against the pack 31 or pulling on the seat 30, the hinge pins 37 will move to the rear until they drop into the notches 27 in which position they cooperate with the notches to provide hinge means upon which the platform deck may be tilted with respect to the base. The stop pins 39 which have at the same time moved to the rear end of the routs 22 prevent downward movement of the rear end of the platform deck, but an upward movement of the rear end of the platform deck and a downward movement of its front end are permitted by passage of the stop pins 39 upwardly through the openings 29 of the routs 22. The platform deck assumes the position shown by the phantom lines of Fig. 2 identified by the letter B, at the beginning of this tilting movement, and assumes the position shown by the phantom lines identified by the letter C at the end of this tilting movement. The movement is limited at position C of the deck by engagement of the underside of the back 31 with the forward cross rail 15 of the base. In this position of the platform deck the back 31 serves as the seat of a child's chair and the seat 30 serves as the back of such a chair. Preferably the weight of the back 31 is sufficient to place the center of gravity of the platform deck substantially in front of the hinge pins 37 with the result that the platform deck will move by gravity from position B to position C.

When the platform deck is placed in position B it also serves as a foot-and-leg rest for a person sitting in a chair located directly to the right of the article of furniture. When used for this purpose the legs of the user are supported by the seat 30, his heels rest upon the forward end of the seat 30 and the soles of his feet rest against the transverse member or back 31 of the platform deck. The platform deck may then be caused to assume any position between positions B and C to suit the comfort of the user, the tendency of the platform deck to move toward position C by the action of gravity causing the seat 30 to comfortably maintain contact with the legs of the user at any desired angle.

The notches 27 are disposed sufficiently near the rear of the base and the seat 30 is of sufficient length that in position B the seat projects substantially to the rear of any portion of the base 11. As the rear end of the seat swings upwardly from position B toward position C, it does not pass forwardly of the rearmost portion of the base until the seat makes a substantial angle with the horizontal. Provision is thus made for the support of the legs of the user as far up as the knees as he sits back properly in the seat of a chair standing to the rear of the foot rest.

To return the platform deck from position B to position A shown in full lines in Fig. 2 the rear end of the platform deck is manually depressed or the front end thereof manually raised causing the platform deck to tilt to a slight angle about the stop pins 39 as a fulcrum elevating the hinge pins 37 out of the notches 27 and the platform deck is then manually moved forward to its low chair position A with the hinge pins 37 seated in the forward ends 23 of the routs 22. To remove the platform deck entirely from the base, the platform deck is placed in position B and then elevated causing the hinge pins 37 to clear the side walls of the notches 27 and the stop pins 39 to move upwardly through the openings 29 and the platform deck is then moved to the rear until the hinge pins 37 reach the end

wall 24 of the rout when the platform deck may be bodily lifted from the base.

Because of the slope of the routs 22, the movement of the platform deck from position B to position A is facilitated by gravity, and for the same reason the platform deck is normally stable in position A. It can, however, be manually moved to the rear from position A to position B by simply applying a small force to the platform deck in the general direction of the axes of the routs. No preliminary elevation of any portion of the platform deck to free it for a rearward movement is required, as would be the case were the pins seated in notches at the front ends of the routs.

In Figs. 5 and 6 is shown an embodiment of the invention in a different form. The article of furniture shown in these figures comprises a base 11a and a platform deck 12a. The base 11a comprises the side elements 13a and 14a joined together by a lower front cross rail 50, a lower rear cross rail 16a, an upper front cross rail 15a, and an upper rear cross rail 51. In this form of the invention the upper cross rails 15a and 51 are preferably bars of rectangular cross section. If desired these upper cross rails may be extended downwardly to the floor 21 and the side elements 13a and 14a may similarly be of generally rectangular shape, extending to the floor 21 and forming with the cross rails a base of box-like character. Such a base may be suitably upholstered on its outer faces. As shown in the drawing, the side elements 13a and 14a each have an upper portion 18a, a front leg 19a and a rear leg 20a.

A guideway 22a in the form of a rout is formed on the inner face of each upper portion 18a of the side elements 13a and 14a. The routs 22a are substantially horizontally disposed and each has a forward slight depression or notch 23a and a similar rear notch or depression 27a. The routs are disposed substantially centrally of the span between the cross rails 15a and 51. Each rout has an upper horizontal wall 25a and a lower horizontal wall 26a and terminates at the notches 23a and 27a.

The platform deck 12a is mounted between the side elements 13a and 14a and comprises a seat 30a and a back 31a. The seat 30a and back 31a are rigidly secured to and between side members 32a, each side member having a horizontal portion 33a and an upright portion 34a all in a manner similar to the form of the invention shown in Figs. 1 to 4, inclusive. The seat and back may be suitably upholstered as at 35a and 36a.

A bar 38a which is secured to the underface of the seat 30a of the platform deck is provided at its ends with oppositely directed hinge pins 37a which project beyond the side members 32a and are seated in the routs 22a respectively.

In using this form of the invention, the platform deck 12a forms with the base 11a a low chair or stool when it occupies the position identified by the letter A' and shown in full lines in Fig. 6. In this position the hinge pins 37a are seated in the forward notches 23a and the front and rear ends of the side members 32a at the same time rest upon the cross rails 15a and 51 respectively. In this position the platform deck is locked by its own weight against movement longitudinally of the base by reason of the engagement of the hinge pins 37a with the notches 23a and is prevented from a tilting movement in either direction by the cross rails 15a and 51.

If now the platform deck be lifted slightly the hinge pins 37a will contact the upper wall 25a of the routs 22a and the platform deck may be then moved rearwardly until the hinge pins 37a drop into the notches 27a. The platform deck is then in the position indicated by the phantom lines designated by the letter B' on Fig. 6.

When the platform deck is in position B', its rear end can not be depressed because of the cross rail 51, but the platform deck may be tilted forwardly and downwardly until it assumes the position shown in phantom lines designated by the letter C' in Fig. 6 when the upper end of the back 31a contacts and rests upon the upper front cross rail 15a. In this form of the invention the platform deck may be so designed that the center of gravity is substantially in the vertical plane of the hinge pins 37a or slightly to the rear of this plane, with the result that it tends to remain stable in either of its positions B' or C' and is easily moved back and forth between these two positions.

The notches 27a are sufficiently near the rear end of the base and the length of the platform between the hinge pins 37 and its rear end is great enough to give it when in position B' a substantial overhang with respect to the rearmost portion of the base 11a. This overhang is sufficient that when the deck is in position C' its rear end extends rearwardly at least as far as any portion of the base 11a. This feature enables a person sitting in a chair placed adjacent the rear end of the base 11a to easily reach the platform deck with his legs and have them comfortably supported thereon as far up as his knees.

As in the form of the invention described in Figs. 1 to 4 inclusive, the platform deck may be provided with guideways and the base with hinge pins without departing from the spirit of the invention. Other changes in design and appearance may also be made without removing the article of furniture from the scope of the invention. With respect to the embodiments of the two forms of the invention herein described, details of construction and design are not to be deemed controlling, but the invention is to be given the scope of the following claims.

I claim as my invention:

1. In a combination footrest and chair, the combination of: a base having side elements; a platform deck extending lengthwise of said base and between said side elements; two oppositely directed horizontal transverse hinge pins carried by said deck intermediate its ends; forwardly and slightly downwardly inclined elongated guideways for said pins on said side elements, each of said hinge pins being slidable within its corresponding guideway and being restrained by said guideway from vertical movement, each of said guideways being upwardly open at its rear end, closed at its forward end, and having at an intermediate point a shallow depression into which the corresponding hinge pin may drop and be held against horizontal displacement; a stop on said base limiting the tilting movement of said deck at a forwardly and downwardly inclined position of said deck when said hinge pins are in said depressions; and two oppositely directed horizontal transverse stop pins carried by said deck, said stop pins being adapted to slidably engage said guideways and be vertically restrained thereby, said stop pins being spaced behind said hinge pins a distance greater than the length of said guideways from said intermediate point to the forward walls of said open ends and greater than the length of

said guideways from said intermediate point to said closed ends.

2. The combination defined in claim 1 in which said platform deck includes a back member at its front end set at approximately at right angle to the deck and extending upwardly with respect to the base.

3. The combination defined in claim 1 in which the deck includes an approximately perpendicularly disposed back member extending upwardly with respect to the base and of sufficient weight to dispose the center of gravity of said deck substantially in front of the axis of said tilting movement when said hinge pins are in said depressions.

4. The combination defined in claim 1 in which the rear ends of said guideways are provided with end walls disposed transversely to the axes of their elongated portions, said end walls being spaced from said intermediate points a distance slightly greater than the distance between said hinge pins and said stop pins.

5. In an article of furniture, the combination

of: a pair of connected parallel side elements, each being provided in its inner side with a longitudinal groove having an upwardly directed opening and sloping from said opening to the front end thereof; a platform member; a pair of pins secured to each side of said platform member and projecting horizontally therefrom, each pin of one pair of said pins being insertable into each of said grooves through said opening by downward movement of said platform member relative to and between said side elements, said platform member being longitudinally movable relative to said side elements when one pair of pins is in each of said grooves or tiltable when only one pin of each said pair is in each of said grooves to permit said platform member to assume any one of a plurality of tilted positions relative to said side elements; and stop means on said side elements and platform for limiting movement of said platform relative to said side elements.

GLENN R. SMITH.
